R. NUTTING.

Running-Gear.

No. 17,805

Patented July 14, 1857.

UNITED STATES PATENT OFFICE.

RUFUS NUTTING, OF RANDOLPH, VERMONT.

MODE OF CONSTRUCTING CARRIAGES.

Specification of Letters Patent No. 17,805, dated July 14, 1857.

To all whom it may concern:

Be it known that I, RUFUS NUTTING, of Randolph, in the county of Orange and State of Vermont, have invented a new and 5 Improved Mode of Constructing Carriages; and I do hereby declare that the following is a full and exact description of the same, reference being had to the accompanying drawings and to the letters of reference 10 marked thereon.

The nature of my invention consists in the construction of compensating springs for buggies and such carriages as require but two springs to support the body in such 15 form that a variety of pressure upon them shall not essentially vary their length; also in so connecting two metallic or wooden springs and triggering rods or straps for carriages with the body and axletrees that 20 they shall answer the fourfold purpose of springs, reaches, braces and rocker, thereby lessening the expense and weight of the carriage, allowing the four wheels to be of equal size, and rendering it an easier conveyance for both the passenger and team. 25

To enable others skilled in the art to make and use my invention I will proceed to describe its construction and operation.

The wheels, axletrees, thills, and body 30 may be constructed in the usual manner; the hind end of each spring A being firmly fastened to the upper side of the hind axletree B, near each end, by being bolted to a cross plate c, which is held by the clasps d, 35 or otherwise, they extend convergingly to the king-plate E, to which they are bolted, and through which the king-bolt F passes and is screwed into the forward axletree G, which should be made lower each side of the 40 central part as seen at G^x, G^x, that the springs H may not hit it in turning the carriage. The chafing iron H'' has an ear I, projecting from it on the inner side, to which the triggering rod or strap K, is connected in any substantial way, the other end 45 being connected to a bar or plate L, projecting forward and downward about four

inches or to a certain point which is always at a certain distance or the same distance from the ear "I," however much the axletree B, may be made to roll by the depression of the springs, for the purpose of preventing any extension of the springs when the wheel suddenly strikes any obstruction, and also for supporting the body in case the 55 spring should break. The central part of the forward axletree M, should be curved a little upon the upper side as seen at N, that the elasticity of the springs may not be restricted. The body may be connected by 60 the spring bars O, to the springs in the common way. The springs should be curved downward near each end just so much that in depressing them those parts below a straight line from one end to the other, P, 65 shall increase in length just as much as that part above, R, decreases, and vice versa.

I am aware that springs have been applied so as to converge from near the extremities of the hind axle, to the fifth wheel on the 70 front axle so as to obviate the necessity of the usual reach, and also that springs of double curvature for producing a compensating effect are in themselves not new; but

What I do claim as new is—

1. The arrangement of compensating springs, substantially as described and specified, with the front and rear axles, so that while the axles are retained in their proper 80 positions, the action of the compensating spring prevents the spreading of the axles on one side of the vehicle, and thereby tends to preserve the accurate tracking of the hind wheels.

2. I also claim the combination of the guard with the hinder part of the springs, substantially as set forth, and for the purposes above specified.

RUFUS NUTTING.
